Patented Aug. 22, 1922.

UNITED STATES PATENT OFFICE.

JOSEPH HREN, OF KINGSTON, NEW YORK.

TROUSERS STRETCHER.

1,426,871.

Specification of Letters Patent. Patented Aug. 22, 1922.

Application filed August 25, 1921. Serial No. 495,351.

To all whom it may concern:

Be it known that I, JOSEPH HREN, a citizen of the United States, and resident of Kingston, county of Ulster, and State of New York, have invented certain new and useful Improvements in Trouser Stretchers, of which the following is a specification.

My invention relates to trouser stretchers of the type which are introduced into the legs of the trousers and has for its object to provide a novel device of the indicated character whereby the trousers are effectively creased and which is particularly adapted for removing bagging at the knees and for otherwise restoring the trousers to its original shape. My invention will be fully described hereinafter and the features of novelty will be pointed out in the appended claims.

20 In the accompanying drawing, which shows an example of my invention without defining its limits, Fig. 1 is an elevation of the trouser stretcher with one of the plates 10 omitted; Fig. 2 is an enlarged detail 25 view of one end thereof; Fig. 3 is a detail section on the line 3—3 of Fig. 2 and Fig. 4 is a similar view on the line 4—4 of Fig. 1.

As shown in the illustrated example the trouser stretcher comprises essentially, a 30 pair of flat longitudinal bars 5 of suitable length and shape and constituting the active 35 creasing and stretching means. These bars 5 are pivotally connected at intermediate points, for instance at 6, with links 7 which 40 themselves are movably connected with each other by means of intermeshing teeth 8 with which said links are provided at their contiguous ends. The links 7, at their intermeshing ends, are further pivoted at 9 between two spaced pivot plates 10, to which 45 one end of a combined adjusting and locking member 11 is also rigidly secured at 12; said member 11 extends lengthwise of the stretcher toward its other end, and is preferably provided with a finger piece 13 or 50 its equivalent for facilitating the manipulation of said member as will appear more fully hereinafter. It will be understood that if desired one of the plates 10 may be omitted, in which case the link 7 and member 11 will be attached only to the remaining plate.

Additional links 14 are pivotally connected at 15 with the ends of said bars 5

and at 16 with an elongated plate or the like 17 which is provided with an opening 18 and with a plurality of apertures 19 arranged in a row, at spaced intervals, lengthwise of said plate 17. The apertures 19 are adapted to receive and co-operate with a projection 20 located upon the member 11, and preferably constructed in the form of a hook as shown in Fig. 3, for the purpose of locking the stretcher in an adjusted position. In the preferred form the member 11 is guided in its lineal movements relatively to the plate 17 by means of guiding lugs 21 formed thereon and projecting over said member 11 as shown in Figs. 2 and 3.

In practice, the device in a folded condition indicated for instance by the dotted lines in Fig. 1, is introduced into the trouser leg after which the links 14 are operated to spread the bars 5 into contact with the trouser material; a pushing force is then exerted upon the member 11, through the medium of the finger piece 12, to actuate the links 7 whereby the connected bars 5 are spread at this point into engagement with said trouser material. The push upon the member 11, brings about a concurrent adjustment of the two links 7, by means of the teeth 8 and is continued to a sufficient extent to cause the bars 5 to exert a stretching pressure upon the trouser leg after which the projection 20 is inserted into the nearest aperture 19 of the plate 17. In this way the material of which the trouser leg is made is placed under tension and by reaction upon the bars 5 exerts a force upon the member 11 in the direction of the arrow in Fig. 1 which tends to maintain the hook or projection 20 in the aperture 19 against accidental displacement; the device is thus locked in its adjusted position and not only efficiently creases the leg of the trousers but also stretches the material thereof in a manner to remove bagginess at the knees and to otherwise restore it to its original shape. When one of the devices has been adjusted in each leg of the trousers the openings 18 may be engaged with a suitable hook or the like to suspend said trousers in an inverted condition whereby the weight of the latter will assist in the functions of the device.

To remove the stretcher it is simply necessary to bend the member 11 as indicated by dotted lines in Fig. 3 to disconnect the hook

20 from the aperture 19, after which the member 11 may be pulled lengthwise to collapse the stretcher back to the dotted position in Fig. 1 in which it may readily be 5 withdrawn from the trousers leg.

The member 11 provides an efficient medium whereby those parts of the bars 5 which are within the trouser leg and not readily accessible, may be accurately manipulated in the desired manner to bring any 10 degree of stretching pressure upon the trousers; the member 11 is made of such length that it extends beyond the trouser leg so as to be easily reached, when the device is operatively combined with said trousers. The 15 plate 17 being also located exteriorly of the latter, in the operative position of the stretcher, no difficulty is experienced in connecting the hook 20 with the proper aperture 20 19 or in disconnecting it therefrom.

The stretcher is simple in construction and positive in its action and provides an efficient device which may be readily manipulated to fit any size or shape of trouser leg 25 to produce any desired degree of stretching strain thereon, whereby the material is effectively creased and restored to its original shape without difficulty; when not in use the stretcher may be compactly folded to occupy 30 a minimum of space.

Various changes in the specific form shown and described may be made within

the scope of the claims without departing from the spirit of my invention.

I claim:—

35 1. A trouser stretcher comprising a pair of spaced, longitudinal bars, a pivot plate, a pair of toothed intermeshing links pivotally connected with said bars and with said pivot plate, a locking plate, a pair of additional links pivotally connected with said bars and with said locking plate, a member connected with said pivot plate and slidably connected with said locking plate whereby said toothed links may be coincidentally adjusted and co-operating means on said locking plate and said member for locking the stretcher in an adjusted position.

40 2. A trouser stretcher comprising a pair of spaced, longitudinal bars, a pivot plate, a pair of toothed intermeshing links pivotally connected with said bars and with said pivot plate, a locking plate, having a series 45 of spaced apertures, a pair of additional links pivotally connected with said bars and with said locking plate, a member rigidly connected with said pivot plate and slidably connected with said locking plate and a hooked projection on said member adapted for insertion into said apertures for locking the stretcher in an adjusted position.

50 In testimony whereof I have signed this specification.

JOSEPH HREN.
